UNITED STATES PATENT OFFICE.

HANS T. SCHEIDACKER, OF BROOKLYN, NEW YORK, ASSIGNOR TO HUDSON BRASS WORKS, INC., OF BROOKLYN, NEW YORK, A CORPORATION OF NEW YORK.

DESIGN FOR A FLOOR LAMP.

Application filed December 27, 1927. Serial No. 24,668. Term of patent 3½ years.

To all whom it may concern:

Be it known that I, HANS T. SCHEIDACKER, a citizen of the German Republic, residing at Brooklyn, in the county of Kings and State of New York, have invented a new, original, and ornamental Design for a Floor Lamp, of which the following is a specification, reference being had to the accompanying drawings, forming part thereof.

Fig. 1 is an elevational view of the lamp showing its general outline with the ornamental details of its top omitted;

Fig. 2 is a similar side view of the same;

Fig. 3 is a plan view of the same showing ornamental details of the top of its base;

Fig. 4 is an enlarged fragmentary elevational view of the top of the lamp showing portions of the ornamental details of the design; and

Fig. 5 is a similar fragmentary side view.

I claim:

The ornamental design for a floor lamp, as shown.

In testimony whereof I have hereunto set my hand.

HANS T. SCHEIDACKER.
